F. CHIAPPARELLI

DOOR HOLDER

Filed Aug. 30, 1926

Fig. 2.

Inventor
Frank Chiapparelli

By Clarence A. O'Brien.

Attorney

UNITED STATES PATENT OFFICE.

FRANK CHIAPPARELLI, OF AROMAS, CALIFORNIA.

DOOR HOLDER.

Application filed August 30, 1926. Serial No. 132,499.

This invention relates to new and useful improvements in holders for retaining swinging doors in open position, the invention aiming to provide a holder preferably for use in association with automobile garage doors so as to permit the operator of a machine to drive the same into the garage without any danger of the door swinging in the direction of the car, which frequently results in damage to fenders, the breakage of windows, et cetera.

One of the main objects of the invention is to provide a holder that is extremely simple of construction, inexpensive of manufacture, and highly efficient in operation.

Other objects will become apparent as the nature of the invention will be understood, the same comprising the novel form, combination, and arrangement of parts hereinafter more fully described, shown in the accompanying drawing and claimed.

In the drawing wherein like reference characters indicate corresponding parts in both of the views:

25 Figure 1 is a detail longitudinal section of the holder, and

Figure 2 is a perspective thereof.

Now having particular reference to the drawing, wherein there is disclosed the most preferred embodiment of the invention with which I am at this time familiar, 5 represents a container preferably of rectangular configuration as disclosed. This container is open at its top side in actual practice, is to be arranged within a pit formed in the floor of the garage adjacent the wall thereof toward which the garage door will swing when being moved to open position.

After the container has been arranged 40 within said pit, a cover plate 6 is disposed thereon, which cover plate is of greater width and length than the container, as disclosed in both the figures. Opposite ends of the cover plate the same are provided with 45 openings 7-7 so that the plate may be secured to the floor surface by bolts, screws or other fastening means 8-8.

Said cover plate 6 is formed with an opening that is of predetermined width and of 50 a length equivalent to the length of the container 5. Pivoted within the container at the top side and adjacent one end as at 9 is an elongated metallic plate 10, that is formed at the pivoted end thereof, and at its top side

with an inclined latch head 11 upon which 55 the lower edge of the door will engage for forcing the plate downwardly against the action of an expansible conical spring 12 bearing at one end upon the bottom wall of the container 5, and at its upper end upon 60 the under side of the plate 10 adjacent the free end thereof. The free end of the plate is formed with a transverse lug 13 that will engage beneath an inwardly directed flange 14 upon the adjacent end of the container 65 for limiting the upward swinging movement of the plate within the container.

The free end of the plate 10 is formed with a vertical foot piece 15 so that the plate can be manually forced downwardly 70 against the action of the spring 12 for obviously permitting the door to be swung in reverse direction over the inclined head 11.

The detail operation of a device of this character will be at once apparent by reviewing the foregoing specification in accompaniment with the present drawing, and even though I have herein shown and described the device as consisting of certain structural elements it is nevertheless to be 75 understood that some changes may be made therein without affecting the spirit and scope of the appended claim.

Having thus described the invention, what I claim as new and desire to secure by Letters Patent is:-

In a door holder of the character described, a container open at its top side only, a lever pivoted at one end within the top side of the casing and at one end thereof, a 90 head formed upon the top surface of the lever adjacent the pivoted end thereof and inclining upwardly from said pivoted end, means within the container for normally maintaining the lever in horizontal position 95 within the open side of the container, a vertical foot piece rising from the free end of the lever being taller than the head and having a lateral extension at its upper end extending away from the free end of the 100 lever, said free end of the lever being provided with a stop projection and said container being provided with a stop projection with which the first projection abuts when the lever is in a horizontal position.

105 In testimony whereof I affix my signature.

FRANK CHIAPPARELLI.
